H. F. HUDSON

RADIATOR PROTECTOR

Filed April 5, 1923

Inventor

H. F. Hudson.

By *A. J. O'Brien*

Attorney

UNITED STATES PATENT OFFICE.

HAVARD FARMER HUDSON, OF WICHITA, KANSAS.

RADIATOR PROTECTOR.

Application filed April 5, 1923. Serial No. 630,012.

To all whom it may concern:

Be it known that I, HAVARD FARMER HU-
SON, a citizen of the United States, residing
at Wichita, county of Sedgwick, and State
of Kansas, have invented certain new and
useful Improvements in Radiator Protec-
tors; and I do declare the following to be a
full, clear, and exact description of the in-
vention, such as will enable others skilled in
10 the art to which it appertains to make and
use the same, reference being had to the ac-
companying drawings, and to the characters
of reference marked thereon, which form a
part of this specification.

15 This invention relates to radiator protec-
tors and has special reference to a protec-
tor that shall be automatic in its operation.

In order to obtain the best results from
an internal combustion engine, it is neces-
20 sary that the temperature of the cooling
water shall be maintained as near as possi-
ble to the optimum.

It has become customary, of late, to secure
25 to the front of the radiator a sheet-metal
protector provided with a number of louvers
that can be opened and closed for the pur-
pose of controlling the amount of air that
can pass through the radiator. In some in-
30 stances the louvers are controlled by a ther-
mostat that adjusts the louvers in accord-
ance with the temperature of the water in
the radiator.

It is the object of this invention to pro-
35 duce an improved protector that shall be so
designed that the louvers cannot be opened
until the water has attained a certain tem-
perature and in which the louvers will be
automatically closed when the gear-shift
40 lever is thrown into neutral position.

In order to more clearly describe my in-
vention, I shall have reference to the accom-
panying drawing in which I have shown
the preferred embodiment thereof, and in
which:

45 Fig. 1 shows a side elevation of a portion
of an automobile, to the radiator of which
my improved protector has been applied,
portions being broken away to better show
the relationship of the parts.

50 Fig. 2 is a perspective view of my protec-
tor.

Fig. 3 is a detail showing the manner in
which the gear-shift lever functions to con-
trol the louvers.

55 Fig. 4 is a perspective view of the con-

trol box, parts thereof being broken away
so as to show the interior.

Fig. 5 shows a perspective of a modified
form of control box; and

Fig. 6 is a section taken on line 6—6, 60
Fig. 5.

The same reference characters will be
used to designate the same parts through-
out the several views.

Numeral 1 designates the radiator of an 65
automobile to which my improved protector
2 has been secured, while 3 designates the
gear-shift lever.

My protector consists of a frame 4 of
sheet-metal, the inner edge of which is bent 70
outwardly to form a flange 5 which fits
against the front of the radiator. Pivotal-
ly connected to the vertical sides of the frame
4 are a number of louvers 6. These louvers
are pivoted near the front edge of the frame 75
and will, unless restrained, assume a sub-
stantially vertical position. Near the top
of my protector there is a shelf 7 to the up-
per surface of which is secured a box 8
which is shown in detail in Fig. 4 and which 80
is constructed as follows: A shaft 9 is rotat-
ably mounted in the ends of the box and is
provided with a number of diametrical pins
10 which make various angles with each
other. Pins 10 may have their ends flattened 85

and made in the shape of a propeller so that
when the wax in the box is in what may be
called the "mushy" state, the pins will tend
to move the wax endwise in the box so that
one pin will tend to close the cut made by the 90
adjacent pin. Rods 11 extend transversely
through the box at points intermediate the
pins 10. A ratchet wheel 12 is non-rotat-
ably secured to the end of shaft 9. A lever
13 is pivotally mounted on the shaft 9 and 95
has attached thereto a pawl 14 which coop-
erates with the teeth on the ratchet wheel.
A spring detent 15 may be secured to the
box so as to prevent rotation of the ratchet
wheel in one direction. If the detent 15 100

were omitted, the friction between the lever
13 and the ratchet wheel 12 would at times
cause the shaft 9 to be rotated in the reverse
direction, which would interfere with the
proper operation of the device. The box 8 105
is filled or partly filled with hydro-carbon,
a wax composition or a readily fusible alloy.
It is evident that with the shaft 9 and pins
10 embedded in wax, the shaft cannot be
turned unless the wax is sufficiently heated 110

so as to be fluid. A rod 16 is pivotally connected to the end of the lever 13 and extends downwardly past all the louvers, the rear edges of which are pivotally attached to the rod at points indicated by numeral 17. It will now be evident that the louvers can only move in unison and that they can be opened only when the shaft 9 can be rotated, whereas they can always be moved from open to closed position.

Secured to the lower louver is a lever 18 to the end of which is fastened a coil spring 19. A piano wire or other flexible connector 20 extends from the upper end of spring 19 to the gear-shift lever 3 and serves to open and close the louvers in a manner that will hereinafter be described. A bracket 21 is secured to the floor of the car, braced from the instrument board, and serves to support the end of a tubular member 22, through which the flexible member 20 extends. At the top of the protector a curved pipe or tube 23, bent at right angles, serves as the guide which permits the flexible member 20 to make the change of direction. Fastened to the engine is a bracket 24 which serves as an anchor for one end of the spring 25, the other end of which is secured to the flexible member 20. Fastened to the gear-shift lever 3 is a short bracket 26 which terminates directly over the open end of the tube 22. The end of the flexible member is fastened to the bracket 26 and its length is adjusted so that when lever 3 is in its neutral position the louvers will be closed. The function of spring 25 is to pull the flexible member 20 forward whenever the lever 3 is moved from any operative to its neutral position.

In Fig. 3 I have shown how the lever 3 will pull the flexible member 20 rearwardly whenever it is moved from neutral to any operative position.

Let us now consider that the parts occupy the position shown in Fig. 1 in which lever 3 is in neutral position and the louvers are closed. Let us further imagine that the radiator is cold and that the wax in box 8 is hard. When the engine has been started and the lever 3 moved to the proper position, the flexible member 20 will put spring 19 under tension and the latter will tend to open the louvers. Since the shaft 9 cannot rotate, the louvers will remain closed until such time as when the radiator becomes sufficiently hot to melt the wax in box 8, when the action of spring 19 will cause them to open.

From the above description, it will be evident that I have produced a radiator protector that is adapted to be applied to the radiator of any ordinary car and which is so designed and constructed that it will not open until the temperature of the radiator water has reached such a point that

the wax in the control box will melt. This assures that the protector will remain closed for some time after the car has first been started, and also assures that it will open before the water gets too hot. By reason of the fact that the protector is controlled from the gear-shift lever, it will always be closed whenever the car is standing still. This prevents any unnecessary cooling of the water.

The control box 8 with its pawl and ratchet connection between the louvers and the shaft 9 and with its detent 15 serves a very important function in the temperature control, as well as in the mechanical control. As explained above, when we start the car on a very cold day, the louvers 6 will remain closed until the engine gets hot and the temperature of the radiator becomes high enough to melt the wax sufficiently to permit the spring 19 to open the louvers by rotating the shaft 9. As we drive along with the louvers wide open, the radiator and the engine will begin to cool and the wax in the control box will soon harden. A condition is now reached in which the engine is too cold and the louvers are in fully opened position. This might be remedied by the driver by moving the gear-shift lever to neutral position for an instant which would permit the louvers to close, but this is obviously impractical.

The louvers, as explained above, are hinged to the sides near the front so that the action of gravity tends to close them. They are, however, held open by the action of spring 19. The spring 19 is selected so that its tension will be sufficient to hold the louvers open under ordinary circumstances, but will permit the louvers to partly close whenever the machine passes over an uneven portion of the road. Let us now consider the case in which the louvers are open and the wax hard, due to a too low temperature. At the first bump in the road the louvers will be moved to partly closed position and will be held in this position by the action of the pawl 14 and the ratchet wheel 12, until the wax softens and permits them to open wider which will only happen if the louvers were closed too much, in which case the wax will soften slowly and permit them to slowly open until the wax hardens a little and holds them from further movement which will then be the proper adjustments for the conditions under which the car operates. If the day is very cold and the louvers did not close sufficiently at the first bump, they will close more when a harder bump is passed. In this manner the opening of the louvers is automatically adjusted to suit the actual conditions of operation with the accuracy of a thermostatic control

and with the added advantage that the

louvers are closed instantly the moment the lever 3 is moved to neutral position, whereas in a thermostatically controlled protector the louvers will not close until the water 5 has been greatly cooled.

I have shown and described the control box which is located on a shelf 8 near the top of the protector. It is essential, however, that the chamber containing the central box shall be lined with a heat-insulating material so that the temperature of the control box will not be unduly affected by the outside temperature, but will maintain a temperature corresponding closely to that 10 of the radiator. It is not absolutely essential that the control box 8 shall be located exactly where it is shown, as it is evident that it may be differently located and still perform its function. I therefore do not 15 desire to be limited to the specific location shown. Although I have shown my device connected to the gear-shift lever of an automobile, I desire to have it understood that it may be connected to any lever which is 20 moved to neutral position when the car is idling. In automobiles having planetary gears there is no gear-shift lever of the type shown, but merely a lever that is moved to neutral position and this lever 25 will perform the same function as lever 3. I therefore desire to have the term "gear-shift lever" to be construed broadly enough to cover both kinds of levers.

It is evident that the function performed 25 by the control box, which has been described above, can be performed by other similar devices of specifically different construction. It is of course impossible to illustrate and describe all the different specific embodiments of this idea and the claims will be relied upon to afford protection for equivalent means. I have, however, shown one modification of the control means, and in 40 Fig. 5 I have shown the modified control box in perspective. The box 8^a, in this instance, is cylindrical and has a shaft 9^a eccentrically mounted for rotation therein. A cylinder 27 (Fig. 6) is non-rotatably 45 mounted on the shaft. This cylinder extends between both ends of the box and is of such a diameter that a small space 28 is left open between the outside of the cylinder 27 and the inside of the box. Flexible blades 50 29 are secured along one side to the cylinder 27 and have their outer edges in contact with the inner surface of the box. The blades 29 extend the entire length of the cylindrical rotor 27. It is evident that if the space between the rotor 27 and box 8^a 55 is filled, or partly filled, with a fusible wax or alloy 30, this will keep the cylinder 27 from being rotated while it is in a solid state. As the wax 30 softens, the cylinder may be rotated if sufficient force is applied 60 thereto, but only very slowly, as the blades

29 will have to force the mushy wax through the restricted opening 28. When the wax becomes sufficiently heated to become a freely flowing fluid, the cylinder 27 may be rotated quite freely as the wax in this state will 70 readily flow through the restricted opening. The mechanism for rotating the shaft 9^a and the cylinder 27 is the same as that described in connection with the box 8 and is indicated by the same numerals. 75

Having now described my invention, what I claim as new is:

1. In combination an automobile radiator; a protector adapted to be secured thereto, said protector having a plurality of louvers 80 hingedly connected thereto; a gear-shift lever; and means comprising a spring connecting said louvers to the gear-shift lever, whereby a force will be produced tending to open said louvers whenever said lever is 85 moved from neutral position.

2. In combination an automobile radiator; a protector adapted to be secured thereto, said protector having a plurality of louvers hinged to the sides thereof and adapted to 90 be opened and closed; means for preventing the louvers from opening when the temperature is below a predetermined amount; a gear-shift lever; means comprising a spring connecting said louvers with said lever, 95 whereby a force is produced that will tend to open the louvers whenever the lever is moved from neutral position.

3. In combination, an automobile radiator; a protector adapted to be secured thereto, said protector having a plurality of louvers hinged to the sides thereof and adapted to be opened and closed; means for preventing the louvers from opening when the temperature is below a predetermined amount, said 100 means comprising a receptacle containing a material that will be hard when below a certain temperature; a shaft rotatable in said receptacle; a number of pins passing through the shaft; means whereby the opening of the louvers tends to rotate said shaft and pins; a gear-shift lever; a flexible member comprising a spring for joining the louvers to the lever; and means whereby when the lever is moved from neutral position, a force will be produced in the flexible member which will tend to cause said 105 louvers to open. 110

4. In combination an automobile radiator; a protector adapted to be secured thereto, 120 said protector having a plurality of louvers hinged to the sides thereof and adapted to be opened and closed; means for preventing the louvers from opening when the temperature is below a predetermined amount, said 125 means comprising a receptacle containing a material that will be hard when below a certain temperature; a shaft rotatable in said box; a number of pins passing through the shaft; means whereby the opening of 130

the louvers tends to rotate said shaft and pins; a gear-shift lever; a flexible member comprising a spring for joining the louvers to the lever; and means whereby when the 5 lever is moved from neutral position, a force will be produced in the flexible member which will tend to cause the said louvers to open; and a spring secured to said flexible member and a stationary part, said spring 10 being so connected that it will be tensioned whenever the lever is moved from neutral position.

5. A radiator protector comprising a casting; a plurality of louvers pivotally connected thereto; means comprising a rod for causing said louvers to move in unison; a receptacle; a shaft rotatably mounted in said receptacle; a ratchet-wheel secured to the end of the shaft; a spring detent engaging 20 said wheel; a lever pivotally connected to the shaft; a pawl on said lever, said pawl being adapted to cooperate with said ratchet-wheel to rotate the shaft as the lever moves in one direction; means connecting said rod 25 and lever, whereby when the louvers move from closed to open position, the shaft will be rotated; a plurality of pins, having flattened angularly placed blades, through said shaft; and a normally solid, but readily 30 softenable material in said receptacle.

6. In combination, an automobile radiator; a protector adapted to be secured thereto, said protector having a plurality of movable members adapted to be opened and closed; 35 means connected to the movable members for preventing the same from opening when the temperature of the radiator is below a predetermined value, said means comprising a receptacle containing a readily fusible material that will be hard when the temperature thereof is below a certain value and will gradually soften as the temperature rises; a movable member within said receptacle, said member being in contact with 40 the fusible material and connected to the first mentioned movable members in such a manner that it will be moved when the first mentioned movable members move to open position, but will remain stationary when 45 the movable members close; and means comprising a resilient member connected to the movable members for imparting to the latter a tendency to open.

7. In combination, an automobile radiator; a protector adapted to be secured thereto, said protector having a plurality of louvers hinged to the sides thereof, said louvers being adapted to be opened and closed; means connected to the louvers for preventing them from being opened while 55 the temperature of the radiator is below a 60

predetermined point, said means comprising a receptacle containing a fusible material that will be hard when below a certain temperature and change gradually from the 65 hard to a liquid form when the temperature increases; a movable member connected to said receptacle and having parts thereof embedded in said fusible material, whereby it will be held from movement while the fusible material is hard; means connecting said louvers to the said movable member, whereby the latter will be moved when the louvers are moved to open position; and means comprising a resilient member attached to the 70 louvers for imparting to them a tendency to open.

8. In combination, a plurality of members adapted to cooperate to open and close an opening; resilient means tending to move 80 said members to open position; means for holding said members in closed position, said means comprising a receptacle containing a material that will be hard when below a predetermined temperature and which will 85 gradually change from hard to fluid state as the temperature increases; a member secured to said receptacle and movable with respect thereto, said member having portions thereof embedded in said fusible material; and 90 means connecting the movable member with said first named members, said means causing the first named members to move the member in the receptacle when the former move from closed to open position.

9. A radiator protector comprising a plurality of louvers, means for mounting said louvers so that they can be moved from open to closed position and vice versa, means comprising a spring for imparting to said 100 louvers a tendency to move to open position and means for holding said louvers against the opening force until the temperature has reached a predetermined value, said means comprising a material that will become soft 105 at the predetermined temperature.

10. A radiator protector comprising in combination, a frame, a plurality of louvers pivoted thereto so as to be relatively movable with respect to each other, means comprising 110 a spring for applying to the louvers a force tending to move them to open position, means for resisting the opening force while the temperature is below a given value and for permitting movement of the louvers to 115 open position after the temperature has risen above the value, said means comprising a normally hard material that becomes plastic above the given temperature.

In testimony whereof I affix my signature.

HAVARD FARMER HUDSON.
